BOAT FENDER

Evan B. Hull, Northboro, Mass., assignor to
Multiform, Inc., Worcester, Mass.

Filed July 12, 1971, Ser. No. 161,404

Term of patent 14 years

Int. Cl. D12—99

U.S. Cl. D71—1 GG

FIG. 1

FIG. 2

FIG. 3

FIG. 5

FIG. 4

FIG. 1 is a perspective view of a boat fender embodying the principles of the present invention,

FIG. 2 is a front elevational view of the fender,

FIG. 3 is a side elevational view of the fender,

FIG. 4 is a bottom view of the fender, and

FIG. 5 is a plan view of the fender.

The rear elevational view of the fender is exactly the same as shown in FIG. 2 and the other side elevational view is exactly the same as shown in FIG. 3.

I claim:

The ornamental design for a boat fender, as shown and described.
